UNITED STATES PATENT OFFICE

CULBERT JAMES PENDER, OF LAUTOKA, FIJI

SUGAR ROLL MILL

Application filed February 25, 1929, Serial No. 342,543, and in Australia March 8, 1928.

The throughput of shredded cane or megass in roller mills in sugar factories is limited by the inability of the rolls to take in megass at the rate at which they are capable of crushing it. The megass tends to crowd at the nip of the front and top rollers. The bulk of the feed is taken by the mill, but the failure of the front and top rollers to take a full nip accounts for a loss in possible throughput 10 which may be estimated at up to 20%.

To augment the intake of feed, sugar mills have been fitted with reciprocating pusher feeders which operate under the feed chute in a horizontal direction to force the megass 15 into the nip of the front and top rollers, but these pushers have provided only a partial remedy for the defect.

The present invention consists in a pusher operating in a vertical direction in co-action 20 with the known pusher equipment which operates in a nearly horizontal direction to compact the feed and enforce the intake of a full feed by the front and top rollers of each mill. The new pusher operates forwardly of 25 the feed plate and in a vertical path or in a path inclined from the vertical, alternating its movements with the movements of the pusher which operates below the feed plate. Whilst the pusher operating under the feed 30 plate forces the feed towards the nip of the rollers, the vertical pusher packs it down on top of the front roller, thus preventing crowding of the feed and packing up against the front aspect of the top roller.

The vertically disposed pusher is preferably hollow, open at the ends and perforated on bottom and sides. Some of the juice which is expressed in the pushing action wells up and passes into the cavity in the pusher 35 through the perforations and flows out through the open ends of the pusher, thence flowing down into the juice pan below the rolls.

Both pushers are driven from eccentrics 45 or cranks on a jack shaft or they may be driven direct from an engine or motor or any other convenient source of motion. The drive is applied through linkage and cranks or otherwise, so arranged as to obtain the alternated movement and appropriate guides

are fitted to maintain the vertical pusher in the designed operative relation to the lower pusher and the front and top rollers. It is practicable to so arrange the pusher drives that both pushers thrust towards the rollers 55 simultaneously but the alternate movement arrangement is preferred.

In the accompanying drawing:—

Fig. 1 is a longitudinal vertical section through the fore part of a three-roller mill to 60 which the invention is applied; and

Fig. 2 is a fragmentary section through the vertical pusher showing the perforations for the intake of the juice during the downward stroke. 65

A is the megass feed chute through which the megass passes to the mill, B is the dead plate, C the top roller, D the front roller, and E the inwardly acting (horizontal or inclined) pusher which forms part of existing 70 mill equipments. F is a shaft, G a crank thereon, H a spring buffer connecting rod, and J an arm on a jack shaft K taking reciprocating motion from the crank G through the connecting rod H. L is another 75 arm on the oscillating jack shaft K, and M a link connecting the arm L of the pusher E.

The novel additional feature in the equipment is the vertical pusher N which operates in a vertical or nearly vertical direction 80 in co-operation with the pusher E. O are guides for the pusher N, P an oscillating arm which drives the pusher N through a link Q, R a jack shaft on which the arm P 85 is keyed, S another arm keyed on the jack shaft R, and T a spring buffer connecting rod between the arm S and a crank U on the shaft F.

The crank throws G and U are set so that 90 the pushers E and N operate alternately, that is to say the forward movement of E takes place during the retiring movement of N and vice versa but this arrangement might be varied to cause both pushers to 95 move forwardly at the same time, or to cause one of them to act more or less later than the other one.

Megass which is pushed towards the rollers by the pusher E tends to crowd up 100

against the front of the top roller. This crowded megass is pushed down by the pusher N. The result of the co-action of the two pushers is to ensure a larger feed of megass into the mill, and consequently to obtain a throughput up to the full capacity of the mill to handle the feed.

In the downstroke of the pusher N the megass suffers compression so that more or less juice is squeezed out of it. To facilitate ejection of this extracted juice, the vertical pusher is preferably hollow. A convenient structural section is shown in Fig. 2 where the shoe of the pusher is formed of a channel W with cheek plates X welded or otherwise fixed to it thus to provide a hollow centre cavity Y. Z are holes drilled through the shoe W and the cheeks X. Extracted juice floods through the holes Z into the cavity Y and flows out of the open ends of the structure, whence it drops into the juice pan.

What I claim as my invention and desire to secure by Letters Patent is:—

1. A feed pusher for sugar mills adapted to act on material entering the expressing rollers including a reciprocable body of hollow form having perforations therein to admit extracted juice.
2. A feed pusher for sugar mills adapted to act on material entering the expressing rollers including a reciprocable body of hollow form having perforations therein to admit extracted juice, said body having terminal perforations permitting the discharge of extracted juice from the pusher.

In testimony whereof I affix my signature.
CULBERT JAMES PENDER.
